UNITED STATES PATENT OFFICE

120,712

DESIGN FOR A REDINGOTE

Samuel E. Frontman, New York, N. Y.

Application February 14, 1940, Serial No. 90,238

Term of patent 3½ years

To all whom it may concern:

Be it known that I, Samuel E. Frontman, a citizen of the United States of America, residing in the city of New York, county of New York, and State of New York, have invented a new, original, and ornamental Design for a Redingote, of which the following is a specification, reference being had to the accompanying drawing, forming part thereof.

Fig. 1 is a front view of a redingote showing my new design.

Fig. 2 is a rear view thereof.

Fig. 3 is an enlarged fragmentary view of the redingote shown in Fig. 1 illustrating one of the pocket members in detail.

The characteristic feature of my design resides in the combination on the redingote disclosed of the specific braid embroidered pocket members in association with the tucked shoulders and the stitched edges, as shown.

I claim:

The ornamental design for a redingote, substantially as shown and described.

SAMUEL E. FRONTMAN.
